UNITED STATES PATENT OFFICE.

HAROLD P. HASTINGS, OF SYRACUSE, NEW YORK, ASSIGNOR TO CROUSE-HINDS COMPANY, OF SYRACUSE, NEW YORK, A CORPORATION OF NEW YORK.

DESIGN FOR AN ELECTRICAL-CONDUIT OUTLET-BOX.

51,960.

Specification for Design.

Patented Apr. 9, 1918.

Application filed July 21, 1914. Serial No. 852,328. Term of patent 14 years.

To all whom it may concern:

Be it known that I, HAROLD P. HASTINGS, a citizen of the United States, residing at Syracuse, in the county of Onondaga and State of New York, have invented a new, original, and ornamental Design for Electrical-Conduit Outlet-Boxes, of which the following is a specification, reference being had to the accompanying drawing, forming a part hereof.

In the drawing, Figures 1 and 2 are perspective views of this electrical conduit outlet box, the box being shown in Fig. 2 as laid over on one longitudinal side.

This design for electrical conduit outlet box includes an elongated body open at one longitudinal side and formed with a part-cylindrical wall 1, at least in cross-section more than one-half of a cylinder, and with a substantially rectangular box-like wall 2 mounted on the part-cylindrical wall 1 and inclosing the longitudinal opening in the open side of the body, the box-like wall having opposing, long, flat and downwardly diverging sides and downwardly diverging rounding ends, the flat sides merging into the part-cylindrical wall above the center thereof, considering the box as in its position shown in Fig. 1.

The box is also formed with nipples 3, 4 at its opposite ends axially aligned with the part-cylindrical wall 1 of the body and of slightly less external diameter than the part-cylindrical wall 1, and also with a third nipple 5 extending laterally with its axis in the same plane as the axes of the former nipples and the part-cylindrical wall, the latter nipple 5 being located midway between the ends of the part-cylindrical wall 1, and having its lower portion substantially flush with the lower face of the part-cylindrical wall 1, that is, with the side of the box opposite the longitudinal open side.

I claim—

The ornamental design for an electrical conduit outlet box substantially as shown and described.

In testimony whereof, I have hereunto signed my name in the presence of two attesting witnesses, at Syracuse, in the county of Onondaga, and State of New York, this 17th day of July, 1914.

HAROLD P. HASTINGS.
